UNITED STATES PATENT OFFICE.

DWIGHT S. RICHARDSON, OF NEW YORK, N. Y.

HOT-AIR HEATING-FURNACE.

No. 909,672.

Specification of Letters Patent.

Patented Jan. 12, 1909.

Application filed February 29, 1908. Serial No. 418,535.

To all whom it may concern:

Be it known that I, DWIGHT S. RICHARDSON, a citizen of the United States, residing at New York, in the county of New York and State of New York, have invented certain new and useful Improvements in Hot-Air Heating-Furnaces; and I do hereby declare the following to be a full, clear, and exact description of the same, reference being had to the accompanying drawings, forming a part of this specification, and to the figures and letters of reference marked thereon.

This invention relates to that type of heating furnaces in which air, usually from an external source, is heated in the spaces surrounding the fire pot and flues and conveyed thence through suitable conduits to the apartments to be heated.

The invention has for its object to provide a construction which will effect a more thorough heating of the air with a minimum consumption of fuel, and especially to provide a construction which will effect a positive or forced circulation of the air into the apartments to be heated, with a provision whereby each or any number of the apartments may be supplied with hot air from its own individual heating channel in order that a difficulty now experienced in forcing the heated air through long ducts or to distant apartments may be effectually overcome.

Referring to the accompanying drawings: Figure 1 is a perspective view partly broken away of a heater embodying the present improvements. Fig. 2 is a sectional view taken on a plane immediately above the body of the heater and below the heating drum, looking downwardly. Fig. 3 is a top plan view of the heating drum and associated parts. Fig. 4 is a detail perspective view showing one of the radiating partition plates with a portion of the top of the heating drum, to illustrate the method of assembling the parts. Fig. 5 is a detail perspective view of a portion of the body of the heater with one of the radiating partition plates in position to be mounted thereon.

Like letters of reference in the several figures illustrate the same parts.

The furnace or heater in connection with which the present invention is illustrated, may be any one of a number of well known types of furnaces which embody a fire pot

section, body section, and heating drum through which the products of combustion are caused to circulate in order that the heat of the same may be effectually transmitted to the air in proximity to the same.

In the drawings, the letter A indicates an ash-pit section, B a fire pot section, and C a body or dome section of a heating furnace. The usual fuel, ash-pit and damper openings are provided for the sections, and as the present invention does not have to do with these particular features, further description is unnecessary. The body or dome section C of the furnace curves inwardly over the fire pot and has a central opening surrounded by a flange c, (Fig. 2), upon which is seated the base of a radiator D, shown in top plan in Fig. 3. This radiator receives the products of combustion through the central opening of the body, conducts them rearwardly through the neck d into the circular peripheral chamber d' in which the said products of combustion travel around to the front of the drum above the intermediate partition d², and at the front pass down below the partition d² and thence around in the chamber d³ to the smoke pipe or exit d⁴. The horse-shoe shaped opening between the center and periphery of the drum constitutes an air heating space through which the air supply is ordinarily conducted into a distributing chamber located above the heating drum and from which the air distributing ducts lead off in various directions, but as said distributing drum and ducts are of well known construction, illustration thereof is not deemed necessary.

Surrounding the several sections of the heater there is the usual sheet-metal casing E, into the lower end of which the fresh air is supplied from any suitable intake.

In accordance with the present invention and in order to subject the fresh air to as large a radiating surface heated by conduction as is possible, as well as to secure certain advantages to be hereinafter referred to, the space in which the air is heated is divided into vertical ducts or channels by radiating partition plates, each having numerous radiating flanges thereon, and each having intimate contact with some portion of the surface of the heater which on one side is subjected to the direct action of the incan-

descent fuel or the heated products and gases emanating therefrom, whereby the entire radiating surface is adapted to be heated by conduction, and such radiating surface is so 5 enormously increased in area as to practically utilize in heating the air, all of the heat unite due to the combustion of the fuel.

In order to make a practical structure from a manufacturer's point of view and to 10 enable the apparatus to be shipped and set up with a minimum amount of labor, not possessing the highest skill, it is desirable to form the radiating partition plates in independent sections adapted to be supported 15 independently by the several sections of the heater. As incidental to this construction, but having an important bearing upon ultimate success of the arrangement, the separation of the radiating partition plates into 20 sections, prevents any breakage or distortion due to the unequal expansion of the several parts going to make up the whole heater, thus, for instance, the fire pot section may expand to a greater extent than the body 25 section, and owing to the separation of the partition plates into sections, the fire pot sections of said radiator plates are free to come and go with the walls of the fire pot section, and this follows true of the other sections of 30 the heater.

The partition and radiating flanges F carried by the fire pot section may, for convenience, be of the construction illustrated and claimed in my prior patent No. 820,130, 35 dated May 8, 1906. All of the radiating and partition plates embody the idea of a central web and vertical lateral flanges f.

The radiating and partition plates G of the body section C conform at their inner edges 40 to the shape of the outer surface of the body section and are conveniently supported at their upper inner corners by a lug or projection g, which is adapted to seat by gravity in or behind a lug g', preferably formed directly on the body section itself (see Fig. 5). In order to hold the radiating plates G in 45 vertical position while permitting them to swing down into intimate and close contact with the surface of the body section, retaining flanges g² and g³ are provided on the body section, the flange g² preferably extending up and merging in the lug g'. In addition a projection g⁴ is provided at the 50 top of the body section to prevent any lateral movement of the plate G, such as would permit the lug g to escape from the lug g'.

It will be understood, of course, that the projections and flanges g², g³ and g⁴ are shown as a convenient means capable of being 60 readily cast integral with the body section, but it is obvious that manufacturers' views with respect to their particular construction will vary, and hence I do not wish to be limited to the particular construction 65 illustrated.

The radiating plates G have their upper edges in proximity to or in contact with the under surface of the drum D, and in the horse-shoe shaped chamber of the said drum, radiating and partition plates H are mounted to form continuations of the radiating and partition plates F and G. The radiating and partition plates H are preferably guided into proper position by shoulders or lugs I, Fig. 4, on the top plates of the drum, 70 and may rest directly on the top edges of the inner portions of the radiator plates G. To hold the plates in proper alinement, downwardly extending fingers h are arranged between the flanges f for embracing the upper 75 edges of the plates G. In addition, the upper ends of the plates H are provided with heads h' adapted to rest on the top of the drum, should there be no other support for said plates H, or in other words, if the plates 80 G are omitted or, as might be desirable in some instances, where they are not located in alinement with the plates H. In the preferred construction, care is taken to so proportion the plates H, G and F, that the 85 flanges f thereon will be in alinement so as to provide for the more ready upward movement of the body of heated air.

The vertical channels or radiating spaces formed by the radiating and partition 90 plates, it is obvious, may be connected at their upper ends, as by a hood C, (dotted lines Fig. 1) with any particular flue through which it is desired to force the circulation of air. To increase the forcing effect it is, in some instances, desirable to extend the length of the vertical heating channels, in which case the outer edges of the plates F and G are surrounded or inclosed by a curved plate L, Figs. 1 and 2. 100

This construction offers no opportunity for the body of warm air forced up through the heater and discharging into the ordinary common distributing drum to return or eddy, and the radiating surface heated by 110 conduction is so greatly increased as to give high efficiency. Where, as most frequently occurs, in installing heating apparatus, some of the distributing mains require a greater pressure than others in order to carry the 115 air to a distant apartment, the vertical air heating chambers connected with those particular flues may be extended down around the fire pot by means of the supplemental inclosing plates L. 120

The arrangement of the parts is such that the heater may be adapted to meet practically any conditions which may be found to exist, and coupled with this adaptability is the great advantage, from a manufacturer's standpoint, resulting from the ability to cast the parts separately, pack them separately for shipment, and to eliminate highly skilled labor in assembling the parts when the plant is installed. 130

Having thus described the invention, what is claimed and desired to be secured by Letters-Patent, is:

1. In an air heating furnace, the combination with the fire pot, body and drum sections, said drum section embodying a center and peripheral flues separated by an air heating space, of vertical radiating partition plates removably suspended from the top of the drum section in the air heating space, radiating plates removably mounted on the body section below the plates on the drum section and independently of the same, radiating plates removably mounted on the fire pot section below the plates on the body section and independently of the same, whereby unbroken air channels are formed

but the radiating plates are free to move with the sections on which they are mounted and heated by conduction.

20

2. In an air heating furnace, the combination with a furnace section exposed on one side to the direct radiation of the fire and having a radial lug and vertical flange formed integral therewith, of a radial radiating plate having a projection in proximity to one edge, said projection being adapted to seat behind the lug and the body of the plate to be positioned by the flange.
